Rodna E. Rodolpha, Chicago, Ill.

Application March 10, 1944, Serial No. 112,857

Term of patent 14 years

(Cl. D58—10)

To all whom it may concern:

Be it known that I, Rodna E. Rodolpha, a citizen of the United States, residing at Chicago, in the county of Cook and State of Illinois, have invented a new, original, and ornamental Design for Bottle Stoppers, of which the following is a specification, reference being had to the accompanying drawing, forming part thereof.

Fig. 1 is a face view of a bottle stopper, showing my new design; and

Fig. 2 is an edge view.

I claim:

The ornamental design for a bottle stopper, as shown.

RODNA E. RODOLPHA.
